TARGET

Fred W. Preece, Toledo, Ohio, assignor to The
 "5" Spot Short Range Gun Clubs of America,
 Inc., Toledo, Ohio, a corporation of Ohio

Application August 20, 1936, Serial No. 97,031

4 Claims. (Cl. 124—15)

This invention relates to game apparatus and is more particularly directed to a target to be used in connection with a game requiring the use of firearms.

5 The primary object of the invention is the provision of a target having a definite conformation such that the success of the player is dependent entirely on the skillful placement of a predetermined number of shots of a specified caliber.

10 Another object of the invention is the provision of a target spot which cannot be completely obliterated in less than the predetermined number of shots allocated to the player.

15 Other objects and advantages of the invention will become apparent as the description proceeds, reference being had to the accompanying drawing, in which—

20 The figure represents one form of target spot diagrammatically associated with circles representing a grouping of shots which will completely obliterate the spot.

25 The invention is intended particularly to be used in connection with a short range gallery in which firearms of a particular caliber, as for example .22 are used. The target spot, shown in the drawing as the numeral "5", is of such a dimension that it is impossible to completely obliterate it with two shots since the size of the figure in each dimension is greater than the caliber of 30 the firearm. Thus, in order to obliterate the spot, at least three perfectly placed shots are required.

35 While the target spot may be of any suitable irregular configuration suitable to enable it to be obliterated by a predetermined number of bullets of predetermined size, it is preferred to limit the number of shots allocated to each player to three in order that the difficulty of the game is not unnecessarily increased.

40 The specific example shown in the drawing consists of a numeral 5, having a maximum width of approximately .23" and a maximum height of approximately .28". Thus, with a .22 caliber firearm no two shots will obliterate the objective spot. In use, it has been found that a bullet 45 from a firearm leaves a hole in a target smaller

than the caliber of the gun so that it is possible to decrease slightly the dimensions given above and still have an objective incapable of obliteration in two shots.

In playing the game, therefore, each player is 5 allowed to shoot three shots from a firearm of a specified caliber at the target. His success is dependent on the successful placing of all three shots since it is impossible to obliterate the target spot in less than this number. This differs 10 from the usual scoring arrangement in connection with shooting since shots that are merely close to the target spot do not contribute to the player's success.

15 While the numeral 5 has been shown as a preferred form of target spot, it should be appreciated that any other irregular figure may be used without departing from the invention as defined in the appended claims.

What I claim is:

20 1. A target for use with firearms of .22 caliber having an objective spot resembling the numeral 5 formed such that the height and width of the spot are greater in size than a hole made by a bullet from the firearm so that a minimum of 25 three shots are required to completely obliterate the objective spot.

2. A target of perforable material having an objective spot comprising a character of distinctly irregular conformation and of a shape and size 30 requiring three predeterminedly placed holes made by three .22 caliber bullets to completely obliterate the spot.

3. A target of perforable material having an objective spot of irregular conformation resembling the numeral 5 with a maximum width of approximately .23" and a maximum length of approximately .28" whereby three .22 caliber bullets are required to completely obliterate the spot.

4. A target of perforable material having an 40 objective spot of irregular form resembling the numeral 5 and requiring three holes made by three differently placed .22 caliber bullets to completely obliterate the spot.
